UNITED STATES PATENT OFFICE.

ALPHEUS J. ALSPACH, OF CHICAGO, OHIO.

COMBINED STEP-LADDER AND IRONING-TABLE.

No. 809,926.

Specification of Letters Patent.

Patented Jan. 16, 1906.

Application filed March 10, 1905. Serial No. 249,458.

To all whom it may concern:

Be it known that I, ALPHEUS J. ALSPACH, a citizen of the United States, residing at Chicago, in the county of Huron and State of Ohio, have invented a new and useful Combined Step-Ladder and Ironing-Table, of which the following is a specification.

This invention relates to combined step-ladders and ironing-tables, and has for its object to simplify and improve the construction and increase the utility and efficiency of devices of this character.

With these and other objects in view, which will appear as the nature of the invention is better understood, the same consists in certain novel features of construction, as herein-after fully described and claimed.

In the accompanying drawings, forming a part of this specification, and in which corresponding parts are denoted by like designating characters, is illustrated the preferred form of embodiment of the invention capable of carrying the same into practical operation.

In the drawings thus employed, Figure 1 is a perspective view of the improved device arranged as an ironing-table. Fig. 2 is a longitudinal section of the upper portion of the device. Fig. 3 is a perspective view of the improved device arranged as a step-ladder. Fig. 4 is a perspective view of the ironing-board from the under side. Fig. 5 is a sectional detail illustrating the position of the parts when the device is arranged as an ironing-table.

The improved device comprises a step-ladder portion 10 of the usual construction and with a relatively broad top or upper step 11, the latter having transverse cleats 12 13 near the ends and a longitudinal cleat 14 depending from the rear edge and extending between the end cleats 12 13, the side members of the step-ladder being rigidly connected to the end cleats. The rear portion or leg is formed in two sections 15 16, the upper section 15 pivoted, as at 17 18, to the end cleats 12 13 and provided at the free end with a transverse member 19, and the lower section pivoted at 20 21 to the upper section and provided with a transverse member 22 and diagonal braces 23 24. The upper section is connected to the step-ladder by jointed bars 25 26, which fold upwardly to permit the lower section to be disposed close to the ladder when not in use. The side members of the lower section diverge toward their free ends to correspond to the diverging side members

of the ladder, so that when folded the lower-section members coincide with the ladder members. The pivots 20 21, by which the lower section is connected to the upper section, are spaced from the lower end of the upper section, and the transverse member 22 of the lower section is spaced from the upper end of the same, so that when the two sections are disposed in longitudinal alignment, as in Fig. 3, or when the device is arranged as a step-ladder the transverse member 19 of the upper section will rest upon the transverse member 22 of the lower section and bear against the diagonal braces 23 24, and to secure the parts in this position the transverse member 22 is provided with a button 42 for extending over the member 19, as shown in Fig. 3. By this simple means a very strong and rigid step-ladder structure is produced, as will be obvious.

The usual swing pail-holding shelf 30 is connected to the upper section 15, as in Fig. 3.

The ironing-table member is represented at 27 with a contracted portion 28 at the larger end and a transverse intermediate stop-cleat 29 on the under side, as shown in Fig. 4.

To transform the device into an ironing-table, it is only necessary to place the ladder in an inclined position, then turn the button 42 to release the lower section, and swing the lower section 16 upon the pivots 20 until the transverse member 22 bears upon the ladder member 10 and against the jointed bars 25 26. The device will then be in the position shown in Fig. 1 with the upper section 15 horizontal. The button 42 is then turned with one end engaging the adjacent step of the ladder structure to prevent displacement of members 16 22. The ironing-board 27 is then placed upon the horizontally-disposed upper section with the contracted end 28 beneath the cleat 14 and the cleat 29 between the side members and against the inner face of the transverse member 19, as represented in Figs. 1 and 2, to complete the arrangement of the device as an ironing-table. A sleeve-board 31 will preferably be swiveled upon the main board 27 for use when required.

The device is simple in construction, can be inexpensively manufactured, and will be found very convenient and useful for the purposes described.

Having thus described the invention, what is claimed is—

A step-ladder having its upper step pro-

vided with a depending cleat, a supporting-leg pivotally connected to said step and formed in two sections pivotally united, the upper section being coupled to the step-ladder by jointed bars and the lower section having a transverse member for bearing upon the ladder portion and against said jointed bars when the lower section is partly collapsed, and an ironing-board for resting upon

the upper section with one end bearing beneath said cleat.

In testimony that I claim the foregoing as my own I have hereto affixed my signature in the presence of two witnesses.

ALPHEUS J. ALSPACH.
